UNITED STATES PATENT OFFICE.

LOUIS GARDNER BOSTEDO, OF ATLANTIC, IOWA, ASSIGNOR TO THE BOSTEDO PACKAGE AND CASH CARRIER COMPANY, OF SAME PLACE.

CASH AND PACKAGE CARRIER.

SPECIFICATION forming part of Letters Patent No. 369,628, dated September 6, 1887.

Application filed August 2, 1886. Serial No. 209,781. (No model.)

To all whom it may concern:

Be it known that I, LOUIS GARDNER BOSTEDO, of Atlantic, in the county of Cass and State of Iowa, have invented certain new and useful Improvements in Cash and Package Carriers; and I do hereby declare the following to be a full, clear, and exact description of the invention, such as will enable others skilled in the art to which it appertains to make and use the same.

My invention relates to an improvement in package and cash carriers.

Hitherto in the package and cash carrying systems in use there has been a great amount of extra labor and expense caused by the necessity of constructing switches at intermediate stations on a line.

The object of my present invention is to provide a system in which the baskets or cars may be put on or taken off the main line directly, thus obviating the necessity of switches, and at the same time leaving the main line complete for the passage of cars to or from other stations, excepting the moment of putting on or taking off a car.

A further object is to make the system as free as possible from complicated parts, and to render the adjustment of a car or its removal from a track simple and capable of being accomplished in a very short time.

With these ends in view my invention consists in forwarding and return tracks provided with removable sections, and a car or basket elevator adapted to remove said sections when the car or basket is elevated and to replace the said sections when the car or basket is lowered.

My invention further consists in certain features of construction and combinations of parts, as will be hereinafter described, and pointed out in the claims.

In the accompanying drawings, Figure 1 is a view in perspective of a section of the tracks, showing the elevator track-section in its lowered position. Fig. 2 is a similar view showing the elevator at a point between the forwarding and return tracks. Fig. 3 is a similar view showing the elevator in its highest position. Fig. 4 is a view of the preferred

form of track-support and car or basket. Fig. 5 is a cross-section through the elevator-guides at the top of one of the tracks, also showing a portion of the elevator; and Fig. 6 is a view in perspective of the end of one section of track.

A represents the forwarding-track; B, the return-track. The tracks A and B are in the same vertical plane and sufficiently far apart at their nearest approach to admit of the free passage of the cash or package car or basket C, which depends from one or more supporting-wheels, c. At each station is located an elevator-guide, D, which consists of one or more vertical rods or bars, preferably two, as shown. The guide-rods D are located a short distance to one side of the tracks, and the portions of the tracks opposite them—viz., a and b—are made removable from the main track. The ends of the main track adjacent to the ends of the removable track-sections a and b are connected by brackets E, which are preferably of rectangular form and are firmly secured to the guide-rods D on their sides opposite the tracks.

The removable section b in the return-track is constructed to rest normally in its position in the track with its upper face flush with the main track, and at the same time be capable of being raised out of its position therein by pressure from the under side. Any well-known or approved means may be employed to cause it to fulfill these conditions. For example, the ends of the removable section b might be grooved, as shown at f, Fig. 6, the grooves being gradually contracted as they extend toward the bottom of the track, and the ends of the removable section b be shaped to register with the said grooves.

The removable section a in the forwarding-track is conveniently provided with a pair of laterally-extending arms, a', attached thereto at or near its ends, the said arms being pivotally secured in the ends of the bracket E, thereby allowing the section a to swing upwardly and over out of the plane of the main track A, as shown in Fig. 3. The removable section a is constructed to rest normally with its upper face flush with the face of the main

track. The means employed for this purpose may consist of lugs a^4 on the bracket E, adapted to engage the lower edges of the arms a' ; or any other well-known or approved means may 5 be adopted.

The elevator consists of a skeleton frame, G, provided with four arms, g , two of which loosely grasp one of the guide-rods and the other two the other guide-rod at points sufficiently far apart to enable the frame to slide freely on the guide-rods without any liability of becoming set by binding. In order to admit of their sliding freely past the points where the brackets E are secured, the socket-bearings in the ends of the grasping-arms g are opened or cut away on their sides opposite the track, as shown at g' in Fig. 5.

To the face of the elevator-supporting frame G is pivotally secured an inverted-T-shaped 20 or three-armed auxiliary supporting-frame, H. The frame H is pivoted to the lower central portion of the frame G, and is allowed a limited tilting movement, enough to enable it to conform to the slant of either the forwarding 25 or returning track, by means of elongated slots h , formed in its arms, through which studs or pins h' , set in the frame G, extend.

To the auxiliary frame H are secured a pair 30 of arms, I, reaching out to the vertical plane of the tracks, and to the ends of the arms is secured the elevator or supplementary track-section K. The elevator track-section K corresponds in length to each of the track-sections a and b , and its ends are so shaped that 35 it will pass freely through the opening left by the removal of the track-section b . A pair of diagonal stay-rods, i, lead from the side of the section K or from the ends of the arms I to the upper portion of the auxiliary frame H.

40 A track-section lifter, L, is secured to the elevator-frame G above the elevator track-section K and in the vertical plane of the tracks. The lifter L is conveniently secured to the elevator-frame by a pair of laterally-extending arms, M, and it is located at such a distance 45 above the elevator track-section K as to admit of the free passage of the car-supporting wheel. The said lifter L is provided with a pair of upwardly-extending pins, l, which are 50 adapted to engage corresponding sockets in the track-section b when the elevator is raised, and thereby lift the said track-section squarely from its position.

The elevator is conveniently raised by means 55 of an operating-cord, O, which extends from its point of attachment on the elevator-frame upwardly and over one or more pulleys, N, and thence downwardly within convenient reach of the operator.

60 When the elevator is not in use, it rests in a convenient position below the two tracks, and the latter are complete, as shown in Fig. 1, and cars to and from the cashier's desk may pass this station without any hinderance.

65 When it is desired to send a package or cash, the car is placed on the elevator track-section

K and the elevator raised until the face of the section K is flush with the main track A, as shown in Fig. 3. In its upward progress the track-section b is lifted from its position by the 70 lifter L, as shown in Fig. 2, and when it reaches the upper track the track-section a is swung out of position and replaced by the elevator track-section K. At the same moment the section K is tilted by any suitable device to 75 conform to the grade of the track A, and the car starts on its passage to the cashier's desk. The elevator is then lowered and the tracks left complete, the section a falling into position by gravity, and the section b being left in position by the lifter until the car is returned, when the elevator will be raised until its track-section is flush with the face of the track B, and when the car rolls onto it and is stopped by a suitable abutment or brake the elevator 80 with car thereon is lowered and the package or cash, or both, delivered.

An approved form of track-support, consisting of a pair of upright rods, P, with skeleton brackets p secured thereto, is shown in 90 Fig. 4, and forms the subject of pending application of Horatio Thomas, filed August 14, 1886, Serial No. 210,910; but other forms might be employed.

The three-armed or inverted-T-shaped frame 95 might also be replaced by a circular or angular shaped plate. The elevator constructed essentially as herein described might also be applied to a single track adapted to answer for both a forwarding and returning truck. 100

Having fully described my invention, what I claim as new, and desire to secure by Letters Patent, is—

1. The combination, with a forwarding-track and a return-track, located one above the other 105 and provided with movable track-sections at each station, of an elevator adapted to raise and lower the car and remove and replace the track-sections, substantially as set forth.

2. The combination, with a forwarding and 110 a return track, each provided with a movable track-section, of a car-elevator provided with a track-section lifter and with a tilting track-section, substantially as set forth.

3. The combination, with a forwarding-track 115 and a return-track, each provided with a removable track-section, of a car-elevator provided with a track-section lifter, and a track-section adapted to replace the removed track-section in both the forwarding and return 120 tracks, substantially as set forth.

4. The combination, with a forwarding-track having a track-section hinged thereto, and a return-track having a track-section removably secured thereto, of a car-elevator adapted to 125 remove and replace the track-sections in its upward and downward passages, respectively, substantially as set forth.

5. The combination, with the forwarding and return tracks, each provided with a removable track-section, and a car-elevator guide located near the removable sections, of

brackets attached firmly to the main tracks and to the elevator-guide, and the elevator adapted to slide up and down on the guide and remove and replace the track-sections, substantially as set forth.

6. In a car-elevator, the combination of the four-armed supporting-frame, the auxiliary supporting-frame, devices for tilting said auxiliary frame, the car-supporting track-section secured to the auxiliary frame, and the track-

section lifter secured to the main supporting-frame, substantially as set forth.

In testimony whereof I have signed this specification in the presence of two subscribing witnesses.

LOUIS GARDNER BOSTEDO.
